UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,347,638.

Specification of Letters Patent.

Patented July 27, 1920.

Application filed April 15, 1919. Serial No. 290,128.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States to O. Mergenthaler, No. 436,532, wherein circulating matrices are released by escapements from a magazine in the order in which their characters are to appear in print and then assembled in line, the composed line transferred to the face of a mold, the 15 mold filled with molten metal to form a slug or linotype against the matrices which produce the type characters thereon, and the matrices thereafter returned through a distributing mechanism to the magazine 20 25 from which they started.

In such machines, the magazine is usually mounted in such manner that it may be quickly removed and replaced by another containing a different matrix font. Before 30 removing the magazine, however, it is customary to lock the matrices therein; in fact, this is necessary when the escapements are supported independently of the magazine, as otherwise the matrices would be free to 35 escape therefrom. Hence, the commercial machines are equipped with devices which will prevent the removal of the magazine until the matrices have first been locked therein, such as shown in the Homans U. S. 40 Letters Patent No. 829,868 and in my pending application, Serial No. 261,000. In the patent, in effecting the removal of the magazine, it is lifted out of engagement with the escapements (which are supported in the machine frame) so that the locking devices are 45 arranged to prevent the premature raising of the magazine; while in the application, before the magazine is removed, the escapements (which are pivotally connected to the 50 magazine base-frame) are lowered out of operative relation to the magazine, so that the locking devices are arranged to prevent the movement of the escapement as distinguished from that of the magazine. In both

cases, however, the locking of the matrices is effected by means of a transverse bar which is inserted through the edge of the magazine in position to engage the upper ears of the lowermost matrices and which, as it is pushed home, disengages the above 55 mentioned locking devices; and to unlock the matrices, the bar is withdrawn or detached from the magazine and laid aside until it becomes necessary to relock the matrices therein; the withdrawal of the bar 60 allowing the locking devices to act in preventing the removal of the magazine. In the use of this detachable matrix locking bar, considerable time is lost in interchanging the magazines, and in addition the bar 65 70 is sometimes difficult to manipulate and quite frequently becomes lost or misplaced, thus occasioning further delay.

My present invention is intended to avoid the foregoing objections and consists in providing the magazine with a permanent matrix locking device which may be instantly moved to active or inactive position at will, and which is arranged to control the magazine locking devices in such manner as to 75 80 permit and prevent the removal of the magazine as the matrices are locked and unlocked, respectively. My invention further contemplates an improved form of matrix locking bar,—one which may be simple 85 in construction, capable of easy and efficient operation, and adapted for universal use.

In the accompanying drawings, I have shown my invention merely in preferred form and by way of example and as applied to the particular style of machine illustrated in the Homans Patent, No. 829,868 but obviously many alterations and variations may be made therein and in its mode of application which will be comprised within its spirit. Thus, it may be applied to other forms of typographical machines, such as illustrated in my pending application above mentioned; or to any other class of machine wherein it is desirable to 90 lock the matrices in the magazine. Generally speaking, I desire it to be understood that I do not limit myself to any specific form or embodiment except in so far as such limitations are specified in the claims.

100 105 Referring to the drawings:

Figure 1 is a top plan view of a magazine equipped with my invention and showing

in particular the relation between the matrix locking bar and the magazine locking latch;

5 Fig. 2 is a vertical section on the line 2—2 of Fig. 1 and showing the matrix locking bar in its inactive position;

10 Figs. 3 and 4 are vertical sections taken through the lower part of the magazine, as in Fig. 2, and showing the matrix locking bar in different positions;

15 Fig. 5 is a detail of a safety latch for the matrix locking bar;

20 Fig. 6 is a top plan view of the lower part of the magazine, partly broken away to expose the matrix locking bar and certain details;

25 Fig. 7 is a section on the line 7—7 of Fig. 6; and

30 Fig. 8 is a bottom plan view of the cover plate forming the lower section of the upper magazine plate and showing the cam control of the matrix locking bar.

35 Referring to Fig. 2, the matrices X are stored in the channeled magazine, A, from which they pass into the assembler entrance or raceway G under the action of the escapements C actuated by the key controlled reeds C¹, the escapements being supported in the bar or frame C² mounted in the fixed machine frame. The side plates of the magazine are formed in their inner faces with the opposing grooves A¹ wherein the projecting ears of the matrices engage, the upper magazine plate having the detachable reinforced cover section A² as usual, and the lower magazine plate having the openings A¹⁰ to receive the grooved portions of the escapement supporting bar C². The magazine is removably supported upon the 40 base frame B which is pivoted at its upper end so as to be swung upwardly to raise the magazine out of engagement with the escapements and to locate it above the assembler entrance G in position for removal, this 45 upward swinging of the base frame being effected by the rotary cams B¹ adapted to coöperate with rollers on the machine frame and fixed to the opposite ends of the rock shaft B² journaled in the base frame and rotated by the handle B³. One of the cams B¹ is formed on its inner face with the lug or stop shoulder B⁴ adapted in the normal or lowered position of the base frame to be 50 engaged by the rear end of the spring-actuated latch or lever C³ centrally pivoted to the escapement supporting bar C² or some other relatively fixed part of the machine.

55 The foregoing parts and their manner of operation are well known and are illustrated and described in the above Homans Patent No. 829,868. In the present instance, therefore, the latch C³, which locks the lifting cams against rotation, serves to prevent the removal of the magazine and the 60 preliminary disengagement or separation of

the escapements until the matrices are locked in the magazine.

As before stated, my invention contemplates a matrix locking device which is permanently mounted on the magazine and which may be instantly moved to active or inactive position at will. In the present instance, such device is in the form of a flat transverse bar E, seated and inclosed with in a corresponding groove A³ formed in the 75 inner face of the detachable magazine section A², the bar being capable of a longitudinal, lateral and edgewise movement in said groove for reasons which will presently appear. Attached to the upper side of 80 the bar (Figs. 6 and 7) are leaf springs E¹ located in further recesses A⁴ of the section A² and having their free ends bearing upon extended portions A⁵ projecting into said recesses, which latter are preferably 85 closed by cover plates A⁶. The springs thus confine the bar in its groove while permitting it to be moved in the three directions stated.

90 As shown in Fig. 1, the relative arrangement of the latch C³ and the bar E is such that the rear end of the former is located in the path of movement of the latter; hence, by a slight longitudinal shifting of the bar to the left, the latch may be disengaged to permit the raising of the magazine for removal. However, means are provided whereby the longitudinal shifting of the bar will move it sidewise or laterally into the magazine for engagement with its matrices. 95 Such means, in the form illustrated, consist of a plurality of buttons or protuberances A⁷ carried by the magazine section A² and fitting in corresponding recesses or depressions E² formed in the upper side of 100 the bar E. When, then, the bar E is shifted longitudinally, its recesses E² will be disengaged from the buttons A⁷, (see dotted line showing in Fig. 7) producing in effect a cam action which displaces the bar laterally or sidewise and projects it into the magazine. Fig. 2 shows the bar in its inactive position and located out of the path of the matrices so as to permit them to pass freely from the magazine; while Fig. 3 110 shows the bar projected into the magazine in position to engage the upper ears of the lowermost matrices and thus to prevent their escape. By shifting the bar longitudinally in opposite directions, therefore, the 115 matrices in the magazine may be locked and unlocked respectively, it being noted that the bar is arranged to disengage the magazine locking latch C³ as it is moved to active position and to permit the engagement or re-engagement of said locking latch as it is restored to inactive position. The bar is preferably formed with a grip portion E⁸ to facilitate its manual operation.

120 In these machines, before separating the 130

magazine and escapements, it is desirable to push the matrices back within the magazine in order to disengage them from the escapements. To effect this result, means are provided whereby the longitudinal shifting of the matrix locking bar to active position will also effect its edgewise displacement rearwardly of the magazine, such action following preferably the lateral displacement before described. In the present instance, such means comprise rollers A⁸ journaled in the magazine section A² and engaging in recesses in the forward edge of the bar E, which recesses are formed so as to present straight surfaces E³ and inclined or cam surfaces E⁴ (Fig. 8). Consequently when the bar is shifted to the left, the rollers A⁸ first track idly upon the straight surfaces E³, during which period the bar is shifted sideways or laterally, and thereafter the rollers engage the inclined or cam surfaces E⁴, which by the continual shifting of the bar displace it bodily edgewise rearwardly of the magazine, as indicated by the dotted lines in Figs. 6 and 8, it being pointed out that the bar is formed in its rear edge with a longitudinal notch or recess E⁵ which permits such edgewise displacement (Fig. 4). When the bar is shifted to the right for re-

turn to inactive position, it is positively moved forward of the magazine in position to enter the groove A³ by means of the co-operating cam surfaces E⁶ and A⁹ formed on the bar and the magazine section A² respectively, see Fig. 8.

The operation of the matrix locking bar may be summarized as follows: The first or initial longitudinal shifting of the bar to the left causes it to be moved from the position shown in Fig. 2 to that shown in Fig. 3, such movement being effected by the disengagement of the buttons A⁷ and the recesses E². The remaining or final longitudinal shifting of the bar causes it to be moved from the position shown in Fig. 3 to that shown in Fig. 4, due to the engagement of the rollers A⁸ and the inclined or cam surfaces E⁴, this final shifting of the bar also rocking the latch C³ about its pivot to disengage it from the stop shoulder B⁴ on the lifting cam B¹. In this condition of the parts, the matrices are pushed back and locked within the magazine and the latter is free to be raised out of engagement with the escapements and located in position for removal; it being noted that the matrix locking bar E and the magazine locking latch C³ are arranged to be disengaged as the magazine is raised by the upward swing-
ing of its supporting base frame. When a new magazine is substituted, the same condition of the parts obtains until the matrix locking bar is shifted to the right to release the matrices. During such rightward shifting of the bar, the cam surfaces E⁶ and A⁹

cause it to be moved forwardly from the position shown in Fig. 4 to that shown in Fig. 3 and the continued shifting of the bar in the same direction brings its recesses E² into registry with the buttons A⁷, whereupon the springs E¹ draw the bar back within the recess A³ from the position shown in Fig. 3 to that shown in Fig. 2. The matrices are thus unlocked and the magazine made ready for use by a slight longitudinal movement of the bar E to the right, this movement at the same time disengaging the bar from the latch C³ and allowing the latter under the action of its spring to reengage the stop shoulder B⁴ to lock the magazine against removal.

To insure the retention of the bar E in its longitudinally shifted position, the magazine section A² is provided with a spring-actuated safety catch or dog F (Figs. 5 and 8) arranged to snap into a recess E⁷ in the end of the bar when in its extreme locking position. The latch is disengaged by hand as the bar is shifted to the right to unlock-
ing position.

It is noted that the bar E is entirely inclosed within the groove A³ and hence offers no obstruction to the use of the magazine. In addition, the form and arrangement of the bar is such that magazines equipped with it may be readily used in machines having magazines equipped with the old form of locking bar. In other words, it is possible to employ in the commercial machines a magazine equipped with the old detachable locking bar or a magazine equipped with my improved locking bar thus permitting a free interchange of magazines, which is of great advantage in view of the number of machines and old magazines now in use.

While I have herein shown and described the matrix locking bar in co-operation with a magazine locking device, it is pointed out that the bar might be employed alone to good advantage or in combination with devices to effect its movements automatically instead of manually, as would be desired for instance in a machine employing a plurality of movable magazines. As previously stated, I have shown my improvements merely in preferred form and by way of example, and obviously many changes, modifications and adaptations will suggest themselves to those skilled in the art without departing from the scope of my invention.

Having thus described my invention, its construction and mode of operation, what I claim and desire to secure by Letters Patent of the United States is as follows:

1. In a typographical machine, the combination of a removable magazine, locking means to hold it in operative position, and a matrix locking device permanently mounted on the magazine and movable to active and inactive position thereon, the said lock-

ing device being arranged to effect the release of the magazine as it is moved to active position.

2. In a typographical machine, the combination of a removable magazine, a spring-actuated locking device to hold it in operative position, and a matrix locking device permanently mounted on the magazine and movable to active and inactive position

10 thereon, the said matrix locking device being arranged to disengage the magazine locking device as it is moved to active position and to permit the engagement of said magazine locking device as it is moved to inactive position.

3. In a typographical machine, the combination of a magazine, a movable supporting frame on which it is removably mounted, a locking device to hold the supporting

20 frame in operative position, and a matrix locking device permanently mounted on the magazine and movable to active and inactive position thereon and arranged to disengage the other locking device as it is moved to

25 active position, the two said locking devices being arranged to be disconnected as the magazine supporting frame is moved from its operative position.

4. In a typographical machine, the combination of a removable magazine, means for moving the magazine from its operative po-

30 sition to permit its removal, a locking device to hold said moving means against operation, and a matrix locking device perma-

35 nently mounted on the magazine and movable to active and inactive position thereon, the said matrix locking device being ar-

40 ranged to effect the disengagement of the other locking device as it is moved to active position.

5. In a typographical machine, the combination of a removable magazine, a locking device to hold it in operative position, a matrix locking device permanently mounted

45 on the magazine and occupying an inactive position thereon and shiftable longitudinally to effect the disengagement of the magazine locking device, and means for

50 moving the matrix locking device to active position as it is shifted longitudinally.

6. In a typographical machine, the combination of a removable magazine, a locking device to hold it in operative position, a matrix locking device permanently mounted

55 on the magazine and standing out of the same and shiftable longitudinally to effect the disengagement of the magazine locking device, and means for moving the matrix locking device into and rearward of the

60 magazine as it is shifted longitudinally.

7. In a typographical machine, the combination with a magazine and a series of escapements therefor, one of said parts be-

65 ing movable out of operative relation to the other, of a locking device to hold said parts

in operative relation, and a matrix locking device permanently mounted on the magazine and movable to active and inactive position thereon, the said matrix locking device being arranged to disengage the other locking device as it is moved to active position. 70

8. In a typographical machine, the combination with a magazine and a series of escapements therefor, one of said parts being movable out of operative relation to the other, of a locking device to hold said parts in operative relation, a matrix locking device permanently mounted on the magazine and occupying an inactive position thereon and shiftable longitudinally thereon to dis- 80 engage the other locking device, and means for moving said matrix locking device to active position as it is shifted longitudinally.

9. In a typographical machine, the combination with a magazine and a series of es- 85 capements therefor, one of said parts being movable out of operative relation to the other, of a locking device to hold said parts in operative relation, a matrix locking de-

vice permanently mounted on the magazine 90 and standing out of the same and shiftable longitudinally thereon to disengage the other locking device, and means for moving

95 said matrix locking device into and rear-

wardly of the magazine as it is shifted lon-

gitudinally.

10. In a typographical machine, the combination with a magazine and a series of es- 100 capements therefor, one of said parts being movable out of operative relation to the other, of a locking device to hold said parts in operative relation, and a movable matrix locking device permanently mounted on the magazine and movable to active and inactive position thereon and arranged to disengage 105 the other locking device as it is moved to active position, the two said locking devices being arranged to be disconnected by the separation of the magazine and escapements.

11. A structure as specified in claim 1, in 110 combination with means for positively holding the matrix locking device in its active position.

12. A linotype magazine provided with a matrix locking bar shiftable longitudinally 115 thereon and means for projecting said bar into the magazine as it is shifted longitudinally.

13. A linotype magazine provided with a matrix locking bar shiftable longitudinally 120 thereon and means for moving said bar rearwardly of the magazine as it is shifted longitudinally.

14. A linotype magazine provided with a matrix locking bar shiftable longitudinally 125 thereon and means for projecting said bar into the magazine and moving it rearwardly thereof as it is shifted longitudinally.

15. A structure as specified in claim 14, characterized by the fact that the means 130

therein recited are constructed to operate in such manner that, in the continued longitudinal shifting of the matrix locking bar, it is first projected into the magazine and thereafter moved rearwardly thereof.

16. A structure as specified in claim 15, characterized by the fact that the means therein recited consist of mutually engaging cam surfaces formed on the magazine and the matrix locking bar.

17. A structure as specified in claim 12, in combination with means for positively holding the locking bar in its longitudinally shifted position.

18. A linotype magazine provided with a matrix locking bar movable both laterally into and out of the magazine and edgewise rearwardly and forwardly thereof.

19. A linotype magazine comprising top and bottom plates formed on their faces with longitudinally extending grooves separated by intermediate ribs, the said magazine being formed in one of its side plates with a transverse groove extending through the ribs thereon and further provided with a matrix locking bar located in said groove and movable bodily into and out of the matrix path.

20. A linotype magazine formed in one of its side plates with a transverse groove and provided with a matrix locking bar inclosed within said groove and movable bodily into and out of the matrix path, said bar being formed with a longitudinal notch to permit it to be moved rearwardly and forwardly of the magazine when projected into said matrix path.

21. A linotype magazine comprising top and bottom plates formed on their inner faces with longitudinally extending grooves separated by intermediate ribs, the said magazine being formed in one of its side plates with a transverse groove extending

through the ribs thereon and provided with a matrix locking bar located within said groove and movable bodily into and out of the matrix path, springs tending constantly to hold the bar within its groove out of said path, and means for holding the bar in said path against the action of the springs.

22. The magazine A formed with the transverse groove A³ and provided with the longitudinally movable bar E located in said groove and formed in its upper face with the recesses or depressions E² engaged with the buttons or protuberances A⁷ on the magazine.

23. The magazine A formed with the transverse groove A³ and provided with the longitudinally movable bar E located in said groove and formed in its upper face with the recesses or depressions E² engaged with the buttons or protuberances A⁷ on the magazine, and with the leaf springs E¹ confining the bar in its groove and normally maintaining the engagement of the buttons and recesses.

24. The magazine A formed with the transverse groove A³ containing the longitudinally shiftable bar E, the latter being formed with the inclined surfaces E⁴ arranged to be engaged by the rollers A⁸ journaled on the magazine.

25. The magazine A formed with the transverse groove A³ containing the longitudinally shiftable bar E, the latter being formed on one edge with the inclined surfaces E⁴ arranged to be engaged by the rollers A⁸ journaled on the magazine, and formed on its opposite edge with the cam surfaces E⁶ arranged to coöperate with similar surfaces A⁹ on the magazine.

In testimony whereof, I have affixed my signature.

DAVID S. KENNEDY.
